LEATHER FRAME

Charles S. Morrison, Elkins Park, Pa., assignor to
Proctor & Schwartz, Incorporated, Philadelphia, Pa., a corporation of Pennsylvania

Application March 24, 1937, Serial No. 132,828

6 Claims. (Cl. 149—21)

This invention relates to frames of the type used for stretching and drying raw or tanned hides, and particularly to frames used in drying leather in a chamber by use of a circulating drying medium therein.

Hides of the larger animals require the use of correspondingly large frames, and in order to accommodate hides of maximum dimensions frames of excessively large areas are required for stretching such hides, in accordance with the current practice. Such excessively large frames necessitate the use of extremely large drying chambers, which in turn require excessive volumes of drying medium. A correspondingly large number of 10 circulating fans or pumps, and heating equipment of sufficient high radiating capacity for properly conditioning the immense volume of air or other drying medium needed, are also required. Large frames such as are used at the present time 15 are heavy and cumbersome to handle.

The principal object of the present invention is to provide a frame capable of handling maximum sized skins and which will be substantially one-half the size of the frames now in use for the 20 same purpose, and by which the size of the drying chamber and its complementary equipment is correspondingly reduced in size and extent.

A second object of the invention is to provide a frame of smaller size and lighter weight but of 25 equal capacity and which may be more readily handled in a relatively smaller space in applying a hide to and removing a hide from the drying frame.

Other features of the invention and the construction and operation of the device constituting the subject matter of the present application will 30 be fully disclosed hereinafter, reference being had to the accompanying drawings, of which:

Fig. 1 is a side elevation of a leather drying 35 frame made in accordance with the principles of the present invention;

Fig. 2 is an enlarged fragmentary view of one corner of the frame shown in Fig. 1;

Fig. 3 is an end elevation of the mechanism 40 shown in Fig. 2;

Fig. 4 is a sectional elevation taken on the line 45 4—4, Fig. 2;

Fig. 5 is a sectional elevation taken on the line 50 5—5, Fig. 1; and

Fig. 6 is a sectional elevation taken on the line 55 6—6, Fig. 1.

As shown in Fig. 1, the device comprises a main frame 1 which in the present instance is of the planar type. The frame 1 in the preferred 55 form disclosed is of a continuous integral hollow

tubular construction and includes end or transverse members 2 and 3 respectively and longitudinal top and bottom members 4 and 5 respectively, with a corner member 6 extending at an angle to and between the transverse member 5 and the longitudinal member 5.

Disposed within the main frame 1 is a metallic sheet 7, which is perforated, as indicated at 8, over substantially its entire area.

The marginal edges of the sheet 7 are reinforced as indicated at 9, such reinforcement, in the preferred form, comprising a sheet of metal folded longitudinally with the edge of the sheet 7 folded in with the metal of the reinforcing sheet 9 and disposed between predetermined layers of the laminated reinforcing edge member 9, as clearly illustrated in Fig. 6.

The sheet 7 is retained in a position inside the frame 1 in a plane substantially coincident with the median plane of the frame 1, by a series of 20 clevises or stirrups 10, shown in detail in Fig. 6, each of which comprises a pair of legs 11, 11 and a cross member 12 connecting said legs to form the U-shaped elements 10. The legs 11, 11 are apertured adjacent their outer ends for the reception of bolts or pins 13 which pass through the stirrup legs 11, 11 and through the sheet 7 and its marginal reinforcement 9 disposed between said legs, as clearly shown in Fig. 6.

The stirrups 10 are secured to the frame 1 by 30 bolts 14 which pass through the frame 1 and the cross members 12 of each stirrup 10 and are threaded into nuts 15 disposed in the stirrups 10 between the legs 11, 11 thereof and resting on and against the cross members 12 thereof. 35

The heads 16 of the bolts 14, in the present instance, are positioned outside the frame 1 and lock nuts 17 are provided between the frame 1 and the stirrups 10 to insure rigidity of the structure. Obviously, the heads 16 of the bolts 14 may 40 be positioned within the stirrups 10 with the nuts 15 disposed on the outer side of the frame, as desired, without departing from the spirit of the invention.

At the corners of the frame where the members 2 and 4 join one with the other and where the members 3 and 4 join one with the other, supplementary perforated sheets 18 and 19 respectively are provided. These supplementary sheets 18 and 19 are of a collapsed U-shaped construction and each include an arcuate portion 20, extending around the frame member 4, and depending portions 21, 21 converging toward the plane of the sheet 7.

The sheet 7 is disposed between the depending 55

portions 21, 21 of the perforated members 18 and 19 with the lower ends 22, 22 of the sheets 18 and 19 disposed in contact with the opposite sides respectively of the sheet 7 and secured thereto by any suitable means, such for example as by spot welding at predetermined points along the edge portions 22, 22 of said sheets.

The arcuate portion 20 of each of the sheets 18 and 19 is spaced from the frame member 4 by 10 semi-circular blocks 23, in the present instance, which, as shown in Fig. 1, are spaced apart longitudinally of the frame member 4.

Rotatably mounted, outside of and parallel to the frame member 4 with its axis substantially in the same median plane of the frame 1 as the sheet 7 is a rockable element in the form of a roller 25. The opposite ends of the rockable element 25 are provided with trunnions 26 and 27 respectively. The trunnion 26 is rotatably 20 mounted in a bearing 28 while the trunnion 27 is rotatably mounted in a bearing 29.

The bearings 28 and 29 are secured to the frame member 4 in any suitable manner, for example in the manner illustrated in detail in Fig. 4, 25 wherein the bearing has a substantially semi-circular foot 30, shaped to fit the curvature of the frame member 4, with a bolt 31 extending through said frame member and threaded into a tapped opening 32 formed in said foot and in 30 an upwardly projecting body portion 33 of the bearing.

The trunnions 26 and 27 are normally mounted for free unrestricted rotation within the bearings 28 and 29 in order that the roller 25 may rock 35 or revolve freely, if desired. However, in order to control the rocking or rotation of the roller 25 one or both of the trunnions of said roller is engaged by a plug 34 of copper, brass, fibre, or other suitable soft metal or frictional material. 40 The friction plug 34 is mounted loosely in a threaded opening 35 formed in the upper end of the body portion 33 of the bearing, with one end engaging the roller trunnion and the opposite end engaged by one end of a screw 36 which is threaded into the opening 35 of the bearing 45 and arranged to be turned to increase or decrease the pressure of the brake plug 34 on the roller trunnion, whereby any desired amount of resistance to the rotation of the roller may be 50 provided.

In the present instance, one or both of the roller trunnions is provided with a collar 37 which is secured to said trunnions by any suitable means such as a headless set screw 38, or the collar may be doweled to the trunnion, if desired. The collar 37 is provided with an arm 39 which under circumstances hereinafter noted 55 may be brought into engagement with a pin 40 which projects laterally from the bearing 29 into the normal path of rotation of the arm 39.

In operation, the frame is preferably held in a vertical position such as shown in Fig. 1, although the frame may be loaded and unloaded in a horizontal position, if desired. The roller 60 25 is turned manually until the arm 39 assumes a position approximating that shown in broken lines in Fig. 3. A hide x is folded and hung over or otherwise placed around the roll 25 with substantially one-half of the hide hanging or otherwise disposed at one side of the frame 1 and the other half of the frame at the opposite side of the frame. The one half of the hide is secured to the sheet 7 by any usual form of toggle (not shown), and which, as is well known 65 in the art, are provided with hooks which may be 70

inserted in the openings 6 of the perforated sheet 7. The toggling of the one-half of the hide x is effected along one longitudinal edge x¹ of the hide at one side of the frame to secure said edge of the hide in position on the frame. The hide is then stretched tightly in a direction transversely to the hide and the frame around roller 5 25 which extends parallel to and along the one marginal edge 4 of the frame and the second longitudinal edge x² of the hide is then secured to the perforated sheet 7, on the opposite side of the frame from that to which the first edge x¹ has been toggled.

In stretching the hide in the above manner, which as noted is transverse to the frame and to the hide, the roller 25 is caused to rock or rotate to some extent, for example until the arm 39 moves from the broken line position in Fig. 3 to the full line position in said figure, the rocking or rotation of the roller 25 being in the direction of the arrow shown in Fig. 3.

After the edges x¹ and x² of the hide x are securely fastened to the sheet 7, in the manner above noted, the substantially coinciding transverse edges x³ at one end of the hides are then secured by toggles of the kind above noted to the sheet 7 and to, for example, the supplementary sheet 18, at each of the opposite sides of the frame 1. The hide is then stretched longitudinally and the transverse edges x⁴ of the hide 30 are then secured to the sheet 7 and to the supplementary sheet 19 by the usual toggles as described above. The hide is then ready for drying.

As the drying of the hide progresses any variations occurring in the tensions of the oppositely disposed halves of the hide resulting from shrinking of the hide as the drying progresses will cause the roller 25 to rock or rotate slightly in one or the other direction in accordance with such shrinkage and the tension created thereby, whereby the hide throughout its entire area from the edge x¹, up the one side of the frame, around the roller 25 and down the opposite side of the frame to the edge x² is maintained under substantially uniform tension, the roller 25 functioning as an equalizer between the two halves 40 of the hide.

The supplementary perforated sheets 18 and 19 make it possible to toggle the hide to the frame close up to the equalizing roller 25, whereby the hide may be held against longitudinal contraction or shrinkage at each side of the equalizing roller 25, whereby the fold in the hide is maintained under uniform tension longitudinally with the other parts of the hide during the drying thereof.

The braking of the roller 25 against free rotation is provided to facilitate the placing of a hide over the frame, before toggling and to prevent the roller from running freely as a result of unbalancing of the hide on one or the other of the opposite sides of the frame, before the hide is toggled in position on the frame.

The frame, as shown in Fig. 1, is adapted to be inserted into a slotted opening formed in one of the walls of a drying chamber into which the frames are normally placed for drying of the hides, and the frame 1 is provided with a slot-closing element 41 which closes the slot in the drying chamber when the frame is fully inserted. The frame 1 is also provided with trunnions 42, 42 by which the frame may be supported during drying and during the placement of the hides on, or the removal of the hides from the frame 1.

A drier of the type in which the frame of the present invention can be readily used is illustrated in each of the prior patents to Walter M. Schwartz and Elwood B. Ayres, No. 1,454,694, dated May 8, 1923, and to Elwood B. Ayres and Alpheus O. Hurxthal, No. 1,567,891, dated December 29, 1925, the former of which also clearly discloses a form of toggle for securing the hide to the stretching and drying frame.

10 I claim:

1. A support for a hide comprising a planar frame, a roller along one edge of the frame around which the hide may be folded with portions thereof disposed at opposite sides respectively of the plane of the frame, and means for applying a definitely determinable retarding force to the rocking motion of said roller transversely to the plane of the frame.

2. A support for a hide comprising a planar frame, a roller along one edge of the frame around which the hide may be folded with portions thereof disposed at opposite sides respectively of the plane of the frame, and means for limiting said rocking motion of said roller transversely to the plane of the frame to substantially a single complete revolution of the roller.

3. A support for a hide comprising a planar frame, a roller along one edge of the frame around which the hide may be folded with portions thereof disposed at opposite sides respectively of the plane of the frame, means for applying a definitely determinable retarding force to the rocking motion of said roller transversely to the plane of the frame, and means for limiting said rocking motion of said roller transversely to the plane of the frame to substantially a single complete revolution of the roller.

4. A support for a hide, comprising a planar

frame, a sole main perforated sheet element rigidly mounted within and secured to the frame in the plane thereof, a roller having a continuous hide supporting face parallel to and spaced from one longitudinal edge of the frame, supplementary perforated sheet elements folded around and disposed at the opposite ends respectively of said longitudinal edge of the frame with depending portions of said supplementary sheets substantially tangent to the peripheral face of the roller and converging toward the main sheet and secured to the opposite ends respectively of the main sheet along the depending edges respectively of the supplemental sheets, the folded portion of said supplementary sheets lying immediately adjacent said roller between said roller and said longitudinal edge of said frame.

5. A support for a hide, comprising a planar frame, a roller adjacent and parallel to one longitudinal edge of said frame, bearings carried by said frame for rotatably supporting the opposite ends respectively of said roller, and a brake plug adjustably mounted in an opening formed in one of said bearings and pressing against the trunnion rotatably mounted therein.

6. A support for a hide, comprising a planar frame, a roller adjacent and parallel to one longitudinal edge of said frame, bearings carried by said frame for rotatably supporting the opposite ends respectively of said roller, an arm rigidly carried by one of said trunnions and extending radially therefrom, and a stop on and projecting from the bearing in which said trunnion is mounted into the normal path of rotation of said arm to limit the extent of rotation of said roller.

CHARLES S. MORRISON.
